VACUUM TUBE

Filed April 5, 1927

Inventor

George H. Perryman
By his Attorney
Harry Redding, Jr.

UNITED STATES PATENT OFFICE

GEORGE H. PERRYMAN, OF WOODCLIFF, NEW JERSEY, ASSIGNOR TO PERRYMAN ELECTRIC CO., INC., A CORPORATION OF DELAWARE

VACUUM TUBE

Application filed April 5, 1927. Serial No. 181,027.

The object of the present invention is to provide an improved vacuum or thermionic device, particularly adapted for radio purposes. My improved tube is so designed as to be readily capable of permitting the heating of its cathode by transformed and stepped down alternating current. I achieve, this, without any trace of an A. C. hum, by the manner in which the filament and the cathode heated thereby are isolated from the anode and grid leads.

Through my improved construction, my improved vacuum tubes may be very expeditiously assembled and furthermore, this assembling is such that an extremely rigid and sturdy construction is provided.

With these objects and such other objects as may hereinafter appear, in view, I have devised the particular arrangement of parts hereinafter set forth and more particularly pointed out in the claims appended hereto.

Reference is to be had to the accompanying drawing, forming a part hereof in which

Figure 1 is a vertical sectional view of a vacuum tube constructed in accordance with my invention.

Figure 2 is a sectional view on the line 2—2 of Figure 1, looking in the direction of the arrows,

Figure 3 is a side elevation of the cathode and attendant parts, with parts of the cathode being broken away to disclose construction and

Figure 4 is a view of a modification.

In the embodiment of my invention as disclosed in the accompanying drawing, 1 indicates the lower stem of the tube. This stem 1 is provided with the usual press 2 and formed integral therewith and extending upwardly therefrom is a projection or stud 3. Extending upwardly from the press 2 is a stem 4 which acts to support the anode or plate 5. Said anode or plate 5 is of the usual tubular form used in many types of various tubes and the same encloses the grid 6. Said grid 6 may be, if desired, composed of a spirally wound wire and the same is supported upon an upright wire or stem 7. The stems 4 and 7 which support the plate and grid respectively have their lower ends con-

nected to lead-in wires 8 and 9 which pass down through the stem 1 and may be connected to prongs of any desired kind mounted on a base which has been omitted for convenience in illustration.

The structure thus far described is, with the exception of the upwardly projecting stud 3 on the stem 2, one which is commonly found in the ordinary vacuum tube construction.

At 10 is shown an upper stem which is provided with a press 11 and integrally formed with said press and extending downwardly from the same is a stud 12. This stud 12 is similar in all respects to the stud 3 on the stem 1. At 13 is shown the cathode which is preferably formed of a section of metal tubular in form and oxide coated. Said cathode 13 is of such internal diameter that its opposite ends fit snugly over the studs 3 and 12 and serve to bridge or connect the same as is clearly illustrated in Figure 1.

The filament leads are disclosed at 14 and 15 and these leads extend downwardly through the stem 10, press 11 and into the internal bore of the tubular cathode 13.

At 16 is shown a spacing member which is in the form of a continuous elongated rod of such a diameter as to fit with a sliding fit within the tubular cathode 13. Said member 16 is in the nature of a support and it is provided with a pair of perforations extending longitudinally through it. These perforations permit the passage of the filament wires indicated at 14 and 15. The filament wires extend through the spacing member 16 and are held rigid and secure therein and connect together at a point below the end of the spacing member 16 as is clearly disclosed in Figure 1.

From the foregoing, the manner in which my improved tube is constructed will be readily apparent. The stem 1 with the anode 5 and grid 6 extending upwardly from it, is assembled in one unit. The upper stem 10 with its parts composed of the cathode 13, the spacing rod 16 and the filaments 14 and 15 fitted in position as is disclosed in Figure 3, is assembled in another unit. The units thus formed are connected together by simply sliding the cathode 13 down within the grid

6 so that the open lower end of said cathode fits over the stud 3 which extends upwardly from the press 2. When this is done, the entire internal parts of the tube have been connected together and furthermore, automatically hold their positions until the tube envelope 17 is fused around them. This is done by first, fusing the stem 10 to one end of the envelope and closing that end and then reversing the tube and fusing the opposite end of the envelope 17 to the stem 1. Thereafter, the tube is exhausted and such bases or terminals as are needed, may be fitted to the tube.

15 I also provide for a cathode lead which automatically establishes connection with the cathode 13 when said cathode is being inserted in position. This cathode lead is shown at 18 and the same passes up through the press 2 and has its upper end terminating in the form of a spring 19. Said spring part 19 normally tends to bear against the surface of the stud 3 and when the cathode 13 is inserted within the anode 5 and the grid 6, 25 and said cathode fits over the stud 3, the end of said cathode 13 passes between the stud 3 and spring 19. Said spring 19 therefore establishes a firm contact against the face of the cathode 13. If desired however, 30 any other form of contact to the cathode 13, in place of the spring 19 can be made.

From the foregoing, it will be seen that the manner of assembling the various elements of my improved tube is such that the 35 tubes can be made rapidly and all of them produced will be made with the same degree of accuracy.

In the tube of the character shown, the filament wires extend out of one end of the tube 40 and the plate and grid leads out of the other with the result that the leads for the filament are spaced away or isolated from the plate and grid leads, so the possibility of an A. C. hum reaching the plate and grid leads is 45 avoided. The filament leads 15 tend, when the necessary current is applied, to heat the cathode 13 in a manner readily understood. Caps of any type may be fitted to the opposite ends of the tube and the leads 9, 18 and 50 8 and the filament leads 14 and 15 may be connected to prongs on such caps to enable the tube to be fitted to sockets provided for them. The construction of the tube is such that the parts may be made heavy and strong 55 so that a tube of long life is provided by the ability of the parts of the tubes to withstand shocks and strains either in transportation or in actual use.

In Figure 4 is shown a modification of my 60 invention wherein the studs that extend into the ends of the tubular cathode 13 are separately formed from the stem 1. In this modification of my invention, the studs are of metal and fit into the presses 2 and 11. When 65 this type of construction is used, the lower

stud which I have indicated at 20 in Figure 4, acts as a termination for the cathode lead 18, thus rendering the use of the spring connection 19 unnecessary.

The filament spacing member 16 may be 70 made of any suitable insulating material such as glass, mica, isolantite or the like. It is preferably made of such diameter that it snugly holds itself within the cathode 13 and its two longitudinally extending openings 75 properly position and hold from displacement the filament leads 14 and 15.

Having described one embodiment of my invention, it is obvious that the same is not to be restricted to the exact embodiment shown, but is broad enough to cover all structures coming within the scope of the annexed claims.

What I claim is:

1. In a vacuum tube, an envelope, an upper 35 stem secured thereto, a lower stem, anode and grid leads extending from the lower stem, said leads carrying an anode and grid respectively, filament leads extending from the upper stem, a projection formed on and extending 40 from the upper stem, a tubular cathode fitted over said projection and extending therefrom, said cathode surrounding the filaments, and a projection on the lower stem over which the lower end of the cathode is 45 fitted.

2. In a vacuum tube, an envelope, a pair of 50 stems fixed thereto, an anode and grid wholly supported by one of said stems, a filament supported by the other stem, said filament-supporting stem being provided with a projecting stud, a tubular cathode surrounding the filament and having one of its ends fitted 55 over said stud and a similar stud on the other stem over which the opposite end of the cathode is fitted.

3. In a vacuum tube, an envelope, a stem attached thereto having an integrally formed 60 projecting stud, an anode and a grid carried by said stem, a tubular cathode fitted over 65 said stud and surrounded by the anode and grid, a second stem on the envelope having a similarly formed stud projecting into the opposite end of the cathode and a filament carried by the second stem and projecting into 70 the cathode.

Signed at the city, county and State of New York, this 2nd day of April, 1927.

G. H. PERRYMAN.
